STOKER

Gordon Simmons, Cleveland, Ohio, assignor to
Carl Smerling and Charles J. Huber

Application November 2, 1929, Serial No. 404,317

3 Claims. (Cl. 110—101)

This invention relates to means for feeding fuel and air to the combustion chamber of a furnace and consists in primarily providing a hopper suitably supported, an air cooled spout for feeding the fuel, means for feeding air thru said spout, means for regulating the fuel and air supply and means whereby the stoker may be adjusted to the height of the furnace door, all as more fully hereinafter described and claimed.

10 An object of the present invention is to provide a stoker which may be readily moved into and out of operative relation to the combustion chamber of the furnace by providing a support for the hopper, spout and regulating means which are 15 pivotally secured to an upright stand.

A further object of the invention is the provision of a stoker which is portably mounted so that the same may be readily moved from place to place including means for raising and lowering 20 the same to meet any height of fire door. This portable device may be mounted on rollers or wheels and provided with means which will release the wheels or rollers from the floor when the stoker is placed in proper position in front of the 25 fire door.

A still further object of the invention is the provision of an air cooled spout for conveying the fuel to the combustion chamber of the furnace. The spout is provided with a trough for 30 feeding of the fuel and beneath this trough is provided an air channel or duct for permitting passage of air therethru, the air cooling the spout and also assisting in combustion of the fuel.

Other objects and advantages of the present 35 invention will become apparent as the description proceeds and as is more fully set forth and claimed.

In the drawings:—

Figure 1 is a side elevation view partly in section.

Figure 2 is a top plan view showing the hopper removed and the support in section.

Figure 3 is an end view.

Figure 4 is a side elevation of a portable 45 stoker.

Figure 5 is a section thru the coupling connected to the ash door.

Referring now in detail to the drawings, 50 represents a hopper provided with an inclined wall and adapted to be filled with coal in any well known manner for feeding the same to a furnace. A member 11 supports the hopper and is provided with an opening 12 thru which a coal pusher bar 13 operates to advance the coal thru the discharge spout 14 into the furnace. The discharge

spout 14 is provided with a flange 15 for rigidly attaching the same to the member 11. The spout 14 is provided with a trough 16 thru which the pusher bar 13 operates to advance into the furnace at predetermined intervals, small quantities 60 of coal received from the hopper 10.

When the stoker is in operation the discharge end of the spout 14 is located above the approximate center of the fire so that the spout and the fuel in the trough are subjected to a considerable 65 amount of heat. This results in partial coking of the fuel with a resulting increase in the efficiency of the furnace. In order to prevent possible destruction of the spout by the heat however, I prefer to provide the lower portion of the spout 70 with an air duct 17 which as here shown is substantially U-shaped in cross section partially surrounding the trough 16, and may be cast integrally with the spout. This duct 17 communicates at one end with a chamber 37 in the member 11, and terminates at the other end in a port 17^a adjacent the tip of the spout. Air is at times supplied to chamber 37 as will be described hereinafter, and this air passing through the duct 17 to the combustion chamber of the furnace, tends 75 to cool the spout and prevent its destruction by the heat of the fire. Furthermore, the air is heated during its passage through the duct 17, so that when it reaches the furnace it assists materially in efficient and rapid combustion. 80

As a further precaution against damage, the spout 14 may be constructed of heat resisting material, or the spout may be provided with a protective sheath 18 of heat resistant or refractory material. As illustrated in the drawings, the 85 lower side of the spout is provided with a removable U-shaped sheath which is retained in position by ribs 19 entering grooves 14^a formed in the sides of the spout. This sheath is also provided with an opening 18^a which registers with duct 17. Should the sheath be destroyed it may easily be removed from the spout and replaced by a perfect sheath.

Positioned between the member 11 and spout 14 100 is a plate 19^a serving as a shield for the furnace door opening. This plate takes the place of the usual furnace door when the stoker is placed in position for feeding the air and fuel thru the spout 14 into the combustion chamber.

Securely mounted upon a base plate 20 is the 105 base 35 supporting a motor 21 having a shaft 22 upon which is mounted a pulley wheel 23 for receiving the belt 24 for establishing a driving connection with the shaft 22 thru pulley 25 for 110

driving the shaft 26. On the shaft 26 is a worm meshing with a reduction gear which may be of conventional form and housed within the casing. A shaft 30 carrying a cam plate 31 is keyed to the gear 29. Eccentrically mounted upon the plate 31 is a member 32 into which is threadedly mounted a rod 33. The opposite end of the rod is threaded into a member 34 to which is pivotally connected the coal pusher rod 13. By providing the rod 33 with screw threaded areas on each end it is capable of adjusting the stroking movement of the pusher rod, if when and as it may be desired to regulate the amount of fuel to be conveyed into the combustion chamber.

15 The motor 21 is mounted upon a base 35 so as to block the same up so that shaft 36 may make a suitable connection with a fan or blower 64 of any desired construction for supplying air to the duct 17 of the spout 14. The air from the blower enters the chamber 37 in the member 11 from where it passes thru duct 17 under the coal conveying trough into the combustion chamber. Mounted on the base of the blower casing is a bracket arm 44 extending outwardly and upwardly therefrom and having a collar for receiving a shaft 45. Adjustably mounted on shaft 45 is a cone 46 adapted to be moved toward and away from the opening in said blower whereby the air may be varied if, when, and as desired.

20 The blower may also be connected to the ash pit by any suitable means, however, preferably as shown in the drawings, by providing the pipe 49 at its lower end with an elbow 49' having a suitable outlet. This elbow outlet is adapted for detachable engagement with a universal joint 51 so that air may be supplied thru the ash door 52 to the under side of the fire bed whereby a supply of air is fed beneath the fuel bed as well as above the fuel bed. The ash door is provided with an opening 54 to which is secured a plate 55 for receiving the threaded end of a pipe 56 which constitutes a portion of the universal connection. This pipe 56 is provided with a cylindrical member 57 threadedly secured upon the outer end of pipe 56 and adapted for universal movement within the housing 58 constituting the other portion of the universal connection. The housing 58 has a spherical portion 59 in which the member 57 is adapted for free universal movement while on the opposite end there is provided an outwardly flared flange 60 adapted to receive the outlet of the elbow thereby establishing suitable connection for supplying air beneath the fuel bed. In this construction it will become apparent that the air feed beneath the fuel bed may be broken when the stoker is withdrawn from the fire door. A suitable damper not shown may be positioned on the base plate 20 for controlling the supply of air thru the pipe and universal connection to the under side of the fire bed.

25 The air passing thru the spout 14 not only serves to cool it but also assists in proper combustion of the fuel due to being discharged above the fire bed. It may be desirable to manually regulate the supply of air to the spout from a point adjacent the spout inlet in addition to the controlling means at the blower. To effect such a desired regulation, I provide a valve 47 in the chamber 37 of member 11 with a manual control 48 for varying the air inlet to said spout. The motor support, blower, and supporting structure for the worm and reducing gearing are all suitably secured to the base plate 20.

30 I prefer to mount the base plate 20, carrying the operating parts, upon a movable carrier to

permit convenient manipulation of the stoker into and out of its operative position. As shown in Figures 1 and 3 for example, the base plate 20 is secured to a supporting block 38, which receives the threaded upper end of an upright pipe support 39. The pipe support 39 is pivotally mounted on a bracket 40 having pivotal connection with a vertical post 41 which therefore serves as the sole support for the stoker and may be mounted in any suitable manner adjacent the furnace.

35 In the modified form of apparatus shown in Figure 4, the hopper 10 and base plate 20, carrying the operating mechanism for the pusher bar 13a, are mounted upon a truck 42 provided with rollers or wheels 43. The wheels 43 may be provided with eccentric levers which will lift the wheels from the floor when the stoker is placed in proper position in front of the firing door. This construction permits the stoker to be portable, yet when the stoker is in operation it will be stationary due to the wheels being lifted from the floor.

40 With either of the illustrated constructions, the stoker may be conveniently moved into its operative position with the spout 14 entering the furnace, and when it is desired to remove the stoker it may be conveniently and quickly withdrawn to inspect the fire, to remove clinkers or for other purposes.

45 By providing a stoker in accordance with the present invention, it is apparent that a much needed improvement in the art has been accomplished. In using the present stoker, it is positioned adjacent the fire door opening, the spout 14 positioned thru the opening into and above the fire bed. Fuel in the hopper 10 is then advanced thru the trough 16 at predetermined intervals. The motor being started operates the pusher rod 13 thru belt 24, shaft 26, conventional type of worm and reduction gearing, shaft 30, cam plate 31 and members 32 and 34 and rod 33, such action resulting in a relatively timed movement of the pusher rod 13 to advance thru trough 16 a desired amount of fuel to the combustion chamber of the furnace. The position of the pusher rod may be adjusted to any desired degree by regulating the distance between the two connecting members 32 and 34. Simultaneously with the advancement of fuel thru the trough 16 air is passed thru the duct 17 of spout 14 into and over the fire bed for cooling the spout and assisting in combustion. The air may be regulated by adjusting the blower inlet. The motor controls simultaneously the feeding of the fuel and air to the spout 14.

50 It is desired to automatically control the operation of the stoker and in this connection a device consisting of a Warren clock 61 is geared to a cam which rotates once per hour and opens and closes contacts in the motor circuit. This may be connected in multiple with the thermostat but in series with the boiler control so that regardless of the thermostat position but subject to position of boiler control, will automatically operate the stoker a predetermined period in every hour, thereby keeping a live fire at all times. This device may be contained in a dust proof box and may be mounted in any desired place or in any convenient manner.

55 Various modifications and minor changes may be made without departing from the spirit of the present invention and as hereinafter claimed.

60 What I claim is:

65 1. In an overfeed stoker for furnaces, a base

150

plate, a fuel feeding mechanism including a hopper having an opening at its lower end and an open end trough extending therefrom secured to said base plate, means for moving the fuel 5 along said trough to discharge the same into the firebox of a furnace, an air conduit being U-shaped in cross section for supplying the air to support combustion of the fuel, the upper portion of which conduit is formed by the sides 10 and bottom of said trough, said conduit having an exit on the underside to discharge the air downwardly onto the fuel in the firebox substantially at the point where the fuel is discharged, the vertical walls of said conduit each 15 having a horizontal groove, a sheath U-shaped in cross section covering the bottom and side walls of said conduit and having an aperture for registering with said exit, means on said sheath for engaging in said groove whereby said 20 sheath may be easily removed and replaced an air pump supplying air to said conduit and means for operating said fuel feeding means and said air pump.

2. In an overfeed furnace stoker, means for

25

feeding fuel to the furnace, a spout for conveying said fuel, air feeding means comprising a conduit in the floor and side walls of the spout whereby air passing thru said conduit tends to cool said spout, said conduit having an exit at the underside of the nose of said spout, and a sheath U-shaped in cross section, shielding the sides and the bottom of the delivery end of said spout and having an opening therein adapted to register with said exit.

3. A stoker comprising a spout adapted to enter the combustion chamber of a furnace to convey fuel and air to the furnace, and a removable channel shaped sheath of fire resistant material shielding the sides and bottom of said spout for protecting the spout from the heat in said chamber, said spout having a trough portion and an air conduit thereunder, said conduit being U-shaped in cross section and surrounding the floor and sidewalls of said trough and having an exit on its under side near the end of the trough, said sheath having an opening near its end registering with said exit.
